JAMES R. MOWAT, OF KEARNY, NEW JERSEY, ASSIGNOR TO THE CLARK THREAD COMPANY, OF NEWARK, NEW JERSEY, A CORPORATION OF NEW JERSEY.

SUPPORT FOR THREAD COPS.

Application filed October 1, 1926. Serial No. 138,820.

The invention relates to an improvement in supports for cops or tubes of thread.

Cops or tubes of thread for supplying high speed sewing machines commonly comprise a cylindrical or cone-shaped core having threads wound thereon in any preferred manner to build up a cylindrical or cone-shaped body. While in use the cop or tube of thread is supported in upright position on a disk-like stand on the sewing machine having a vertically arranged post to prevent the cop from accidental displacement. It has been found that as the thread is drawn off from the cylindrical or cone-shaped body 10 cam loops of thread sometimes fall down onto the stand and pass under the lower end of the cop of thread so that the thread is broken, thereby necessitating rethreading of the needle and consequent stoppage of work. Accordingly, there have been many efforts, some of them patented, to interpose means 20 between the support on the sewing machine and the bottom of the cop of thread to prevent the loops of thread from passing under the bottom of the cop of thread. Some of the prior devices proposed for preventing the loops of thread from passing under the cop of thread and breaking have proved unsatisfactory because they have not provided 30 means for fixedly securing the cop to the support, and other devices which have provided means for securely fastening the cop to the support have proved unsatisfactory because they have been relatively complicated in construction and consequently expensive to manufacture.

One object of the present invention is to produce an improved support for cops or tubes of thread of such construction that the 40 cop of thread will be held firmly on the support without liability of accidental displacement therefrom, so that the loops of thread which fall onto the support will have no opportunity to pass under the cop of thread and be broken. Another object of the invention is to construct the support in such manner that a partly used cop of thread may be removed from the support and again replaced thereon and yet be held firmly in 45 operative position. A further object of the invention is to provide a thread cop support of this character with means whereby both cylindrical and cone-shaped cops may be supported from the same disk or plate. To these ends the invention consists in the im-

proved support for cops or tubes of thread hereinafter fully described and particularly pointed out in the appended claims.

In the accompanying drawings illustrating the preferred form of the invention, Fig. 1 is a perspective view of a form of support adapted for cylindrical cops; Fig. 2 is a side elevation of a cylindrical cop or tube of thread in position on the support, the lower part of the figure being shown in section; Fig. 3 is a top plan of a form of support adapted for cone-shaped cops; and Fig. 4 is a side elevation of a cone-shaped cop or tube of thread supported in position on the support shown in Fig. 3, with the bottom of the figure shown in section.

The improved support for cops or tubes of thread illustrated in Figs. 1 and 2 comprises a disk or plate 5 which is preferably composed of metal having at its center an upright externally threaded bushing 6. The disk 5 and the bushing 6 are inseparably connected, as by riveting, welding, or the like. The disk and bushing are provided with a central hole adapting them to be placed over and held by the usual upstanding post on the support connected with the sewing machine. Overlying the upper surface of the metal disk 5 is a pad 7 of some yielding material such as felt against which the bottom of the body of thread 8 on the cop or tube is adapted to rest. The disk 5 and pad 7 are substantially larger in diameter than the body of thread 8 wound on the cop, as shown in Fig. 2, so that the loops 80 of thread falling from the thread body 8 rest on the projecting rim of the pad 7.

The threaded bushing 6 is of such size in external diameter that it may be screwed into the lower end of the cylindrical cop or tube 10 on which the layers of thread 8 are wound. In order that the bushing 6 may be more readily screwed into the lower end of the cylindrical cop or tube 10 and cut a thread therein, the bushing 6 is provided with a plurality of vertical slots 11, four being shown in the drawings, which cause the bushing to act as a tap, so that as the bushing is screwed into the end of the cop 10 the front or advancing faces of the slots 105 11 cut a thread into the fibrous or other relatively soft material of which the cop is composed. The slots 11 not only constitute the bushing in effect a tap but also lend resiliency to the walls or spaces of the bushing 6 110

2
 between the slots 11, so that when the bushing 6 is in place in the lower end of a cop, as shown in Fig. 2, the walls of the bushing will exert a pressure on the walls of the cop 5 tending to hold the two together. When the improved thread cop support consisting of the disk 5, resilient pad 7 and threaded bushing 6 is to be connected with the lower end 10 of a cop or tube of thread, the spiral threads on the bushing 6 enable the operator to establish a very tight engagement between the lower end of the body of threads 8 and the upper surface of the resilient pad 7, in effect burying the bottom of the body of threads 8 15 in the soft yielding material 7, thereby effectively preventing any loops of thread which fall down onto the rim of the pad 7 from passing under the body of thread. The threads cut into the lower end of the cop 20 by the bushing 6 enable the cop of thread to be removed and replaced again, the corresponding threads on each part again engaging each other and causing the lower end of the thread body 8 to press tightly 25 against the upper surface of the felt pad 7.

In the form of the invention shown in Figs. 3 and 4 the disk 12, resilient pad 13 and threaded bushing 14 are of the same construction as the corresponding parts 30 shown in Figs. 1 and 2. In order to adapt this form of thread support for holding cones of thread 15 wound on a hollow cone-like core 16, I provide an auxiliary ring or bushing 17 threaded internally to screw onto the bushing 14 and provided externally with 35 a threaded surface 18 having the same taper as the cone-shaped cop 16 and of a size adapting it to screw into the lower end of the cop 16. By reference to Fig. 3 it will 40 be seen that the ring 17 is provided with the vertical slots 19 which constitute it a tap in the same manner in which the slots 11 constitute the bushing 6 a tap, so that as the ring is screwed into the lower end of a cop

16 the front or advancing faces of the slots 45 19 cut a thread into the lower end of the cop 16. This enables the cone of thread 15 to be screwed tightly onto the support shown in Figs. 3 and 4, with the bottom of the body 50 of thread buried firmly in the pad of yielding material 13. In this form of support also the cop of thread may be removed from its support in case another size or color of thread is to be used, and then replaced, the threads in the bottom of the cop readily 55 engaging the corresponding threads on the bushing 17.

Having thus described the invention what I claim as new is:—

1. A support for a cop of thread comprising, a disk, a hollow bushing projecting upwardly from the disk and having an external thread adapting it to be screwed into the bottom end of the cop, said bushing being provided with a plurality of longitudinal 60 slots dividing the bushing into a plurality of resilient walls adapted to press yieldingly against the inner surface of the cop, the front faces of the slots acting to cut a thread in the bottom of the cop as the bushing is 65 screwed therein, and a pad of yielding material covering the upper surface of the disk and against which the bottom of the body of thread is adapted to press when the bushing is screwed fully into the bottom of the 70 cop.

2. A support for a cop of thread comprising, a disk, and a hollow bushing projecting from the center of the disk and provided externally with a thread adapting it to be 80 screwed into the bottom end of the cop, said bushing being provided with a plurality of longitudinal slots dividing the bushing into a plurality of resilient walls which yieldingly press outwardly against the inner surface of the bottom end of the cop. 85

JAMES R. MOWAT.
